UNITED STATES PATENT OFFICE.

GEORGE E. CURTISS, OF NEW BRITAIN, CONNECTICUT, ASSIGNOR TO LANDERS, FRARY AND CLARK, OF NEW BRITAIN, CONNECTICUT, A CORPORATION OF CONNECTICUT.

DESIGN FOR A COFFEEPOT.

Application filed April 21, 1923. Serial No. 5,885. Term of patent 14 years.

To all whom it may concern:

Be it known that I, GEORGE E. CURTISS, a citizen of the United States, residing at New Britain, county of Hartford, and State of Connecticut, have invented a new, original, and ornamental Design for Coffeepots, fully described and represented in the following specification and the accompanying drawings, forming a part of the same.

The drawing is a perspective view of a coffeepot showing the new design.

What is claimed is:—

The ornamental design for a coffeepot as shown.

GEORGE E. CURTISS.
